RECIPE CARD HOLDER

Carl J. Dexter, 130 Hideaway Lane,
West Lafayette, Ind. 47906

Filed June 14, 1973, Ser. No. 370,175

Term of patent 14 years

Int. Cl. D6—06

U.S. Cl. D6—85

Fig. 1

Fig. 2

Fig. 3

Fig. 4

Fig. 5

Fig.6

Fig.7

Fig.8

Fig.9

Fig.10

FIG. 1 is a front elevation view of my recipe card holder showing my new design;

FIG. 2 is a rear elevation view thereof;

FIG. 3 is a left side elevation view thereof, the right side being a mirror image of it;

FIG. 4 is a top plan view thereof;

FIG. 5 is a bottom plan view thereof;

FIG. 6 is a front elevation view of a modified form of my recipe card holder showing my new design;

FIG. 7 is a rear elevation view thereof;

FIG. 8 is a left side elevation view thereof, the right side being a mirror image of it;

FIG. 9 is a top plan view thereof; and,

FIG. 10 is a bottom plan view thereof.

The broken line showing of a recipe card in FIGS. 1 and 6 is for illustrative purposes only and forms no part of the claimed design.

I claim:

The ornamental design for a recipe card holder, as shown and described.
